FILING DEVICE

Daniel A. Brennan, deceased, late of Chicago, Ill.,
by Elmer L. Zwickel, executor, Chicago, Ill., as-
signor to Acco Products, Inc., Long Island City,
N. Y., a corporation of New York

Original application June 21, 1939, Serial No.
280,267. Divided and this application April 20,
1942, Serial No. 439,695

4 Claims. (Cl. 129—25)

This application is a division carved out of application Serial No. 280,267, filed June 21, 1939, now Patent No. 2,280,184, dated April 21, 1942.

The invention relates to improvements in fastening devices and more practically to paper fastener bases including means to detachably secure the base to a file folder or backing.

An object of the present invention is to provide a paper fastener base of a type having bendable sheet receiving prongs with novelly formed means for slidably and frictionably engaging or co-acting with novel means on a file folder or backing to detachably secure a sheaf of sheets carried on said base to the backing; said means consisting of inter-engaging parts, disposed wholly below the plane of the sheets, arranged to keep the assembly to a minimum thickness.

An object is to provide a novel mounting for a paper fastener base with resilient means to frictionally bind the base thereto to prevent inadvertent separation of the parts and which is easily manipulated to facilitate separation when desired.

Another object is to provide a novelly constructed paper fastener base and file mounting which are inexpensive to construct, simple to operate, and highly efficient in use.

Another object is to provide a filing device of the character described which does not materially increase the thickness of a file.

The foregoing and such other objects of the invention as will appear hereinafter as the description proceeds, will be more readily understood from the perusal of the following description, in which reference is had to the accompanying drawing wherein:

Fig. 1 is a perspective view of a fastener base showing it attached to a portion of a file folder or backing.

Fig. 2 is a transverse sectional view taken substantially on line 2—2 of Fig. 1.

The base 11 is of a type having an intermediate body portion with bendable prongs 12, provided one at each end, adapted to be disposed substantially at right angles to the intermediate portion to threadingly receive thereon a plurality of perforated sheets of paper to be bound in a file. When thus arranged, the portions of the prongs extending through the sheaf of papers are threaded through openings in an associated compressor (not shown) and then bent down flat against the top face of said compressor to prevent separation. In the structure illustrated, the base 11 is formed to co-operate with a mounting mem-

ber 13 to facilitate ready attachment of the sheaf of paper to a folder or backing sheet A.

The present invention is intended primarily to facilitate mounting or removal of a sheaf of bound papers in the file without damage to the bottom sheet of the stack which normally occurs in known types of mountings due to physical contact with said sheet by the mounting member during relative movement of the parts. Such a mounting organization must, however, be such that the stack of sheets may easily and quickly be mounted or removed without detracting from the need for a relatively rigid not easily separated fastening means.

Referring specifically to the construction illustrated, the intermediate portion of the base 11 has its longitudinal side margins offset downwardly from the normal plane of said intermediate portion to define opposed longitudinal flanges 14. The flanges 14, in effect, define an elevated central portion 15 in the base which lies tightly against the bottom face of the stack of papers when the latter is positioned thereon, thereby retaining said stack spaced from said flanges. The base is consequently admirably adapted for use in association with a mounting member preferably of the type shown at 13 which is suitably secured in any practical manner to one face of the file folder or backing A.

As shown, the mounting member may consist of a substantially elongated strip of stiff material, such as sheet metal, having one longitudinal edge turned upwardly and then inwardly to define an overhanging lip 16 co-extensive with one longitudinal edge thereto. The other longitudinal edge of said mounting member 13 has an upwardly extending resilient lip or latch 17, which may terminate short of each end of the member for a purpose to be better understood as the description proceeds.

To mount the base 11 on a mounting member, one of its longitudinal flanges 14 is inserted, while the base is tilted transversely as shown in dotted lines in Fig. 2, beneath the overhanging lip 16, and the base is shifted transversely while being swung downwardly parallel thereto. This movement of the base positions the said flange 14 entirely beneath the overhanging lip 16 and the other longitudinal base flange 14 is forcibly urged downwardly past the resilient lip 17 whereupon the base is detachably secured and retained in superposed relation on the mounting member. Inadvertent shifting or removal of the base is prevented primarily by the binding and frictional engagement of the resilient lip 17 with one flange

14 and also by means of at least one pair of co-acting detents 18 and recesses 19 provided, respectively, in the overhanging lip 16 and underlying flange 14.

It should be apparent at this time, that sheets carried on the base 11 are held spaced above the mounting member 13 and its effective parts, in a manner to prevent damage to any of the sheets by such parts. If desired, the base member 11 may be removed from the mounting member 13 by shifting it longitudinally relatively thereto until the frictionally engaged flange 14 is clear of the resilient latch 17.

It should be apparent that a fastening device is provided which may be economically manufactured and which includes provisions for detachably securing a sheaf of papers to a backing sheet or file. The bound stack of papers may be removed readily from the file for use or for placing in any other file without disturbing the papers, and the papers may be as easily replaced in the file by properly locating the co-acting formations on the associated parts and moving one relative to the other.

What is claimed is:

1. In a filing device, a base having spaced apart prongs to receive a plurality of sheets of paper threaded thereon, said base having its longitudinal margins offset between said prongs to define longitudinal flanges in a plane below the remaining base portion, a mounting member, an elevated flange on one longitudinal edge of said mounting member to receive one of the base flanges therebeneath when the base is disposed in a laterally tilted position over said mounting member, and means on the other longitudinal edge of said mounting member to engage over the other longitudinal base flange when the base is swung downwardly into a horizontal plane to detachably connect and retain said base in superposed relation on said mounting member.

2. In a filing device, a base having spaced apart prongs to receive a plurality of sheets of paper threaded thereon, said base having its longitudinal margins offset between said prongs to define

longitudinal flanges in a plane below the remaining base portion, a mounting member, an elevated flange co-extensive with one longitudinal edge of said mounting member to receive one of the base flanges therebeneath when the base is disposed over said mounting member, and a resilient lip on the other longitudinal edge of said mounting member to frictionally and bindingly engage the other longitudinal base flange to detachably connect and retain said base in superposed relation on said mounting member.

3. In a filing device, a base having spaced apart prongs to receive a plurality of sheets of paper threaded thereon, said base having its longitudinal margins offset between said prongs to define longitudinal flanges in a plane below the remaining base portion, a mounting member, an elevated flange on said mounting member to receive one of the base flanges therebeneath when the base is disposed over said mounting member, and a resilient lip on said mounting member to frictionally and bindingly engage the other longitudinal base flange to detachably connect and retain said base in superposed relation on said mounting member.

4. In a filing device, a base having spaced apart prongs to receive a plurality of sheets of paper threaded thereon, said base having its longitudinal margins offset between said prongs to define longitudinal flanges in a plane below the remaining base portion, a mounting member, an elevated flange on said mounting member to receive one of the base flanges therebeneath when the base is disposed over said mounting member, and means on said mounting member to frictionally and bindingly engage the other longitudinal base flange to detachably connect and retain said base in superposed relation on said mounting member, said elevated flange and means being disposed wholly below the plane of the said remaining base portion.
